CLAIM

The ornamental design for an adjustable neck support for attachment to an automobile headrest, as shown and described.

DESCRIPTION

FIG. 1 is a left side elevational view of an adjustable neck support for attachment to an automobile headrest showing our new design, the broken-line showing of the individual's head and the automobile seatback being for illustrative purposes only and forming no part the claimed design;

FIG. 2 is an enlarged top plan view thereof;

FIG. 3 is an enlarged left side elevational view thereof;

FIG. 4 is an enlarged front elevational view thereof;

FIG. 5 is an enlarged bottom plan view thereof;

FIG. 6 is an enlarged right side elevational view thereof; and

FIG. 7 is an enlarged rear elevational view thereof.
